SYSTEM OF TRANSLATING THE MINUTE VARIATION OF INDUCTANCE OR CAPACITY INTO THE VARIATION OF ELECTRIC CURRENT OR VOLTAGE

Hitoshi Inoue, Shimo Takaido, Suginami-Ku,
Tokyo, JapanApplication September 26, 1939, Serial No. 296,572
In Japan September 30, 1938

1 Claim. (Cl. 175—183)

This invention relates to a system of translating the minute variation of inductance or capacity into the variation of electric current or voltage, which consists in impressing high frequency voltage upon the screen grids of tetrode or pentode valves from a separate high frequency oscillator, and on the other hand forming a tuning circuit including inductance or capacity under measurement; connecting said circuit to the control grid of the concerned for completing the grid circuit; feeding the voltage of the oscillator to said tuning circuit through the inter-electrode capacity between the electrodes between the above mentioned two grids or by using also the outer connecting circuit; inserting an automatic bias device consisting of grid leak resistance and by-pass condenser into the cathode return of the above grid circuit varying the plate current of said valve by utilizing the quick variation of the high frequency voltage phase of the tuning circuit and the variation of the control grid voltage when the minute change of the test capacity or inductance occurs, and thus translating the minute variation of capacity or inductance into the corresponding change of voltage or current. The object of the present invention is to provide a system for improving the sensibility, accuracy and stability of such a circuit system as utilizes phase shifting due to the variation of the resonant frequency tuning circuit, especially for easily obtaining a desirable long maintenance of calibration hitherto considered difficult in this kind of circuit, by improving and simplifying the known system a great deal, and also by using the variation of the control grid voltage due to the tuning frequency.

Referring to the appended drawing.

Figure 1 is a diagram of an electrical connection showing an example of the manner of carrying out the present system into practice;

Figure 2 is a graphic explanation of a relation between two control grids in the phase of electric potential;

Figure 3 a diagram showing the phase variation due to capacity variation;

Figure 4 is a diagram showing the operation of this system.

In Figure 1, the output of an oscillator 1 is transmitted into a coupling coil 2, thus causing the fall of the voltage to both terminals of a tuning circuit comprising a coil 2' and condenser 3, and feeding said voltage to a suitable vacuum valve, for instance, to the screen grid electrode 5 of a pentode 4. The plate current of said valve is able to flow only when the screen grid 5 is at

positive half cycle of the given high frequency oscillation. The mean value of the plate current is determined by the control grid voltage—both amplitude and the relative phase relation to the screen grid voltage phase—under the constant plate voltage and the constant screen grid excitation. The control grid 6 is connected to the tuning circuit 7, which is composed of condenser 8 under measurement, condenser 10, and coil 9. Said tuning circuit, approximately tuned to the oscillator frequency, is supplied high frequency voltage from the oscillator through the inter-electrode capacity between control grid 6 and screen grid 5. Grid leak resistance 11 and bypass condenser 12 are provided as an automatic bias device using grid current. Thus, the potential of the control grid 6 is given as the superposition of both the high frequency drop voltage across the tuning circuit 7 and D. C. bias voltage across resistance 11.

Next, to explain the operation of the above system, Figure 2 shows a relation between the voltages of the screen grid and the control grid. Figure 3 illustrates that the phase of the terminal voltage of the tuning circuit varies at the detuning of said circuit. If the potentials of the grids 5 and 6 are then given the same phase by adjusting the capacity 10 of the tuning circuit 7 in Figure 1, the plate current of the vacuum valve 4 will show the maximum value. That is, when the potential of the control grid has the same phase as the screen grid potential as illustrated at (2B), the indication of an ammeter 13 shown in Figure 1 will show the maximum value.

Next, if the value of the test capacity 8 changes by ΔC from the above condition, a difference in the phase of voltage between the grids 5 and 6 will become θ , and the plate current gradually decreases as θ increases according to the value of ΔC . Figure 2 illustrates this performance; an area having hatching lines indicates the part where the plate current cannot flow and accordingly the greater that part is, the smaller the plate current will be. That is to say, the value of ΔC causes the great or small variation of θ and the great or small variation of θ produces the corresponding degree of the plate current. In other words, the degree of the variation of the test capacity may be measured by that of the plate current. A resistance 14 translates the plate current variation into voltage variation, if necessary. It is also the case with the variation of the inductance 9.

The above explanation shows briefly the oper-

ation and idea of the present system with regard to a phase relation, but in practice this system operates in a somewhat more complicated form. That is to say, so long as the anode 5 voltage is not extremely great, the plate current begins to flow from the point

$$\omega = \frac{1}{L(C+C_0)\left(1 + \frac{1}{Q^2}\right)}$$

10 and increases with the increment of the test capacity C or test inductance L. In the above formula, ω represents oscillator angular frequency; L, the inductance of the coil 9 in Figure 1; C, 15 the sum of the capacity of the condensers 8 and 10, and C_0 , the coupling capacity between the grids 5 and 6. For the purpose of increasing C, the outer capacity may be added in parallel between the grids 5 and 6. Q represents

$$20 \quad \frac{WL}{R}$$

at the tuning circuit 7. R is the loss resistance in the above circuit 7.

25 The point shown by the above formula, the starting point of the plate current, indicates the tuning point of the whole grid circuit including the coupling capacity C_0 . The high frequency voltage of the grid 6 shows the maximum value 30 at that point and the phase difference between the grids 5 and 6 is 90° . Figure 4 illustrates a relation between the variations of high frequency control grid voltage E_g and plate current I_p . As C or L increases, or in other words, the phase 35 difference between the voltages of the grids 5 and 6 is reduced, the plate current increases and at the same time the high frequency voltage E_g applied to the grid 6 is reduced quickly.

It must be noted here that the present system 40 utilizes an automatic bias device consisting of a resistance 11 and capacity 12 as an automatic bias for the grid 6. It is the well-known fact that in the bias system employing grid current, the plate current increases with the reduction of the high 45 frequency voltage impressed on the control grid. In this system, the high frequency voltage pressed upon the grid 6 is greatest when the plate current begins to flow. With reduction of the phase difference from this point, the voltage of the grid 6 50 is simultaneously reduced, and by their co-operation the plate current is considerably increased. Thus, since this system uses the phase variation and voltage variation together instead of being the mere combination of a tuning circuit and 55 phase meter, it is able to operate with very high sensibility.

Next, let me explain what characteristic feature this invention has as compared with the known systems. The systems for measuring 60 minute variation of capacity or inductance have been studied for more than ten years, because they are very useful for measuring mechanical displacement through a medium of capacity or inductance, whose value is varied by mechanical 65 displacement under measurement.

One of the most effective systems is such a one as to utilize the rapid phase change of the high frequency voltage across the resonant circuit under shifting of its tuning frequency.

70 By utilizing such a system ingeniously, Olinphant has succeeded in measuring and recording the variation of the pressure of fluid. He has also published its application to other fields in "The Journal of Scientific Instruments," pages 75 386-388, of Dec. 1932.

My system too utilizes the phase shifting phenomenon of the tuning circuit, but unlike the known circuit, it has such remarkable features as utilize voltage variation also.

The novel feature of the present invention consists in making a vacuum valve phase and voltmeter by a new circuit system, combining it ingeniously with the tuning circuit including a test article by a new process, and utilizing both the phase difference and voltage variation by using 10 an automatic bias, and thus translating minute capacity or minute inductance variation into large current or voltage variation.

The following points form the main basis which has enabled a system of high sensibility, remarkable accuracy, great stability and simple construction to be materialized in manufacturing a system for translating capacity or inductance variation into current or voltage variation by utilizing high frequency. It indeed forms the 20 nucleus of my invention.

(1) A tuning circuit including a test article is used without load.

(2) Voltage is supplied to the test circuit by 25 utilizing the capacity between the inner grids of the vacuum valve, thus taking the terminal voltage of the tuning circuit comprising the coil 2' and condenser 3 in Figure 1 at the standard vector, and putting the phase variation of the 30 screen grid voltage due to the undesirable variation of the constants of said circuit out of the question.

(3) The screen grid is not provided with any other energy supply source than the output of the 35 high frequency oscillator, and it is so devised that absolutely no self-oscillation occurs, even if tuning circuits are provided simultaneously at the two control electrodes of one vacuum valve.

(4) If the detuning of the tuning circuit, comprising the test article in Figure 1 reaches a certain limit, the plate current becomes zero, and if it is turned to the opposite direction, the plate current reaches a saturation value which may be easily brought into agreement with the given value of the first calibration by varying the degree of the coupling of the output of the oscillator 1, or by adjusting the tuning circuit 3 shown in the above figure. In this way, the long maintenance of calibration as is difficult in this kind of circuit 45 may be obtained easily by simply keeping constant the value of the inductance 9.

In accordance with the abovementioned features of the present invention, it is possible to overcome the many technical difficulties encountered in manufacturing the system for translating the variation of capacity or inductance into that of current or voltage and to increase the stability, accuracy and sensibility and also simplify the construction, of the system.

According to my experiment, if in this system a valve (UZ57) is used as a detecting vacuum valve and a valve (6L6) used as a crystal controlled oscillator and oscillation frequency 3500 kc. is adopted, the plate voltage supply is 250 65 volts, and the capacity of the tuning circuit 7 is about 100 micromicrofarads, then the variation of the plate current when unloaded is 10.5 microamperes for the variation $\frac{1}{1000}$ micromicrofarad of the capacity in the tuning circuit. Also, if in the same condition a resistance of 500,000 ohms is inserted into plate circuit, the voltage variation across it is 2.75 volts per $\frac{1}{1000}$ micromicrofarad and the range of the voltage variation is 0-220 70 volts.

Judging from the stability of the circuit of this invention, meters or relays can be operated by utilizing such minute variation of the capacity as $\frac{1}{10,000}$ micromicrofarad. A concrete circuit capable of detecting such minute capacity variation so easily has never been expected. Indeed, the present circuit contributes a great deal to the improvement of the electrical and mechanical engineering arts.

10 Having now fully described my invention, I claim:

System of translating the minute variation of inductance or capacity into the corresponding change of current or voltage, which comprises a 15 valve which is at least a tetrode valve and may be pentode valve, a separate high frequency oscillator for impressing high frequency voltage upon the screen grid of said valve, a separate tuning circuit including inductance or capacity 20 under measurement, said tuning circuit being

connected to the control grid of the valve for completing a control grid circuit and supplied with the high frequency voltage through the interelectrode capacity between screen grid and control grid or outer feeding circuit, and an automatic bias device consisting of grid leak resistance and by-pass condenser, inserted in the cathode return of the control grid circuit, producing control grid voltage variation, and quick variation of the phase difference between control grid 10 and screen grid voltage, which are due to the variation of the resonant frequency of said tuning circuit caused by the change of inductance or capacity under measurement, so as to utilize both variations in order to produce the change of 15 the plate current of said valve and translate the minute variation of capacity or inductance into the corresponding change of voltage or current.
